UNITED STATES PATENT OFFICE.

FRED W. MILLER, OF KENMORE, NEW YORK, ASSIGNOR TO CLIMAX CABINET COMPANY INC., OF BUFFALO, NEW YORK.

PIANO-PLAYER-ROLL CONTAINER.

1,374,462.

Specification of Letters Patent. Patented Apr. 12, 1921.

Application filed April 17, 1919. Serial No. 290,801.

To all whom it may concern:

Be it known that I, FRED W. MILLER, a citizen of the United States, residing at Kenmore, in the county of Erie and State of New York, have invented a new and useful 5 Piano-Player-Roll Container, of which the following is a specification.

The device forming the subject matter of 10 this application is adapted to be employed for displaying conveniently, music rolls of the sort used in connection with mechanical pianos, organs, music boxes and the like.

One object of the invention is to provide 15 novel means for holding the music rolls on the conveyer or carrier chains.

Another object is to provide means whereby the rolls will be prevented from unwinding while they are on the carrier chains.

20 Another object of the invention is so to construct the carriers that rolls of different diameters may be accommodated readily. A further object of the invention is to provide an indicating mechanism whereby the 25 operator at will, may bring any desired roll to the top of the cabinet for removal. General improvements in devices of the kind described are contemplated, and will manifest 30 themselves as the description proceeds.

Within the scope of what is claimed, 35 changes prompted by the skill of a mechanic may be made, without departing from the spirit of the invention.

In the drawings:—

Figure 1 shows in front elevation, a music 40 cabinet constructed in accordance with the invention, parts being broken away and parts appearing in section; Fig. 2 is a vertical section in a plane extended from the front of the cabinet to the back thereof; Fig. 45 3 is an elevation showing a portion of the carrier, a music roll being mounted therein, and parts appearing in section; Fig. 4 is an elevation showing the indicating mechanism; Fig. 5 is a vertical section taken 50 through the structure shown in Fig. 4; Fig. 6 is a sectional detail disclosing the part of the carrier and the music roll, together with the means for preventing the roll from unwinding; Fig. 7 is a view of operating handle.

The invention comprises a cabinet, denoted generally by the numeral 1 and including a box-like body 2 and a lid 3, hinged at its rear edge, as shown at 4, to the body 55 2. Any desired number of carriers for the music roller may be provided, but since the carriers are alike, but one carrier will be mentioned in the following description.

Standards 5 are mounted on the upper 60 end of the cabinet 1, at the front and at the back thereof, beneath the lid 3, and in the upper ends of the standards, a main shaft 6 is journaled for rotation, the shaft being held against endwise movement by collars 7 65 or the like, attached to the shaft and coacting with the upper ends of the standards 5, the standards, obviously, constituting bearings for the main shaft. The forward end of the main shaft 6 is provided with a cross 70 pin 8 or like projection, adapted to be received in the slot 9 of a crank 10 which, being mounted on the forward end of the main shaft 6 constitutes a means whereby the main shaft may be rotated and the carrier 75 on said shaft actuated.

Sprocket wheels 11, which may be in the form of disks, are secured to the main shaft 6 adjacent to the front of the cabinet and adjacent to the back thereof, the wheels 80 having hubs 12 attached to the shaft 6 by means of securing elements 14, the wheels 11 having peripheral seats 15. The invention contemplates the use of a carrier, made up of two chains comprising links 16, each 85 link being offset at one end, as shown at 17, to overlap the corresponding end of an adjoining link, the ends of the links being connected by pivot elements 18. Cross members 19 are provided, the same having rectangularly disposed ends 20 mounted to swing on the pivot elements 18. The cross members 19, therefore, may be described as being mounted eccentrically at their ends, 90 on the chains of the carrier. The cross members 19 of the carrier are connected by retractile springs 21. In oppositely disposed links 16 of the carrier chains, supports 22 are mounted. For convenience in manufacture, the supports 22 on the respective chains 100 are alike, and are of tubular form, the supports being contracted at their outer ends as

shown at 23, and being provided at their outer ends with openings 24. In the supports 22 of one carrier chain, plungers 25 are mounted to reciprocate, the plungers 5 being supplied at their inner ends with heads 26. Compression springs 27 surround the plungers 25 and are located in the corresponding supports 22, the outer extremities of the springs abutting against the contracted ends 23 of the supports, and the inner ends of the springs abutting against the heads 26 of the plungers 25.

The numeral 40 marks a spool of the kind commonly constituting a part of a music roll, the spool carrying a sheet 41 wound on the spool. One end of the spool 40 is placed on the support 22 which, as shown in Fig. 3, is devoid of a spring-actuated plunger, the other end of the spool being 15 engaged by the head 26 of the plunger 25. Obviously, by retracting the plunger 25, the music rolls can be mounted on the carrier and be disengaged therefrom without difficulty. Referring particularly to Fig. 6, it 20 can be seen that the retractile springs 21 which connect the cross members 19 of the carrier, bear on the sheet 41 of the spool 40 and prevent the sheet from unwinding. There is a distinct advantage in supplying 25 the cross members 19 with the offset ends 20 which are mounted on the pivot elements 18. Since the cross members 19 are terminally mounted, eccentrically, on the chains of the carrier, the cross members can move 30 toward and away from each other transversely, thereby adapting the carrier to accommodate music rolls of different diameters. When the crank 10 is applied to the 35 forwardly projecting end of the shaft 6, the shaft 6 and the sprocket wheels 11 will be rotated. The supports 22 project beyond the respective carrier chains and are received in the seats 15 of the sprocket 40 wheels. The supports 22, therefore, exercise a double function, in that they constitute a means for holding the music rolls 45 on the carrier, and constitute, also, a means whereby the carrier is operatively connected with the sprocket wheels. It will be clear 50 that when the shaft 6 is rotated as aforesaid, along with the sprocket wheel 11, the carriers will be operated, thus bringing one music roll after another up to the top of the body 2 of the cabinet so that any music 55 roll may be removed at will. When the lid 3 is closed on the body 2 all of the music rolls are housed in and shielded against dust and against damage from any other cause.

The invention includes an indicating 60 mechanism, whereby the operator may be advised when any particular roll has arrived at a position at the top of the cabinet. This indicating mechanism includes a fixed pointer or index 28 secured at 29 to the

forward standard 5, the shaft 6 passing 65 through the index. The shaft 6 serves to prevent the index from swinging on the securing element 29, and, upon the other hand, the index affords an additional bearing for the shaft 6. The index 28 coöperates with 70 a dial 30 having a scale 31 of any desired sort, the dial being secured at 32 to a gear wheel 33 mounted to rotate on the shaft 6 and meshing into a pinion 34 secured to an auxiliary shaft 35 journaled in the lower 75 end of a hanger 36 carried by the shaft 6, the shaft being rotatable in the upper end of the hanger. A gear wheel 37 is secured to the shaft 35, the gear wheel 37 and the pinion 34 being located on opposite sides 80 of the lower end of the hanger 36. The gear wheel 37 meshes into a pinion 38 secured at 39 to the corresponding sprocket wheel 11 at the front of the cabinet.

When the shaft 6 is rotated, rotation will 85 be imparted to the sprocket wheel 11 (Figs. 4 and 5) as aforesaid, the sprocket wheel 11 rotating the pinion 38 and the pinion 38 rotating the gear wheel 37. From the gear wheel 37, rotation is imparted to the pinion 90 34 by way of the shaft 35, the pinion 34 rotating the gear wheel 33 and the dial 30, so that the scale 31 thereof coöperates with the upper end of the fixed index 28. The combined weight of the lower end of the 95 hanger 36, the pinion 34 and the gear wheel 37 is sufficient to maintain the hanger in the depending position shown in Fig. 5 and to prevent the hanger from swinging on the shaft 6 when the operation last-mentioned takes place. It will be clear that if the music rolls are numbered, and are placed in the upper location on the carrier, the operator, glancing at the place where the index 28 coöperates with the dial 30 100 105 can ascertain when any desired music roll has arrived at the top of the cabinet.

Having thus described the invention, what is claimed is:—

1. A device of the class described comprising a frame; a shaft journaled therein; wheels on the shaft and having peripheral notches; endless conveyers; tubular supports mounted intermediate their ends in the conveyers, the outer ends of the supports being received in the notches of the wheels to form a driving connection between the wheels and the conveyers, the inner end of one support constituting means for engaging one end of a music roll; and a plunger mounted in the other support and constituting means for engaging the opposite end of a music roll, the tubular construction of the supports permitting the plunger to be mounted in either support at 125 the will of an operator.

2. A device of the class described comprising a frame; a shaft therein; endless

conveyers coöperating with the shaft and having music roll supporting means; connections having their ends pivoted eccentrically to the conveyers, whereby the connections may be swung toward and away from each other, transversely, thereby to accommodate music rolls of different diam-

eters; and retractile members uniting the connections and constituting retainers for the free ends of the sheets of the music rolls.¹⁰

In testimony that I claim the foregoing as my own, I have hereto affixed my signature.

FRED W. MILLER.
